UNITED STATES PATENT OFFICE.

ISAAC SMITH ROSS, OF WOODWARD, OKLAHOMA.

DEVICE FOR IDENTIFYING GARMENTS AND HEADWEAR.

No. 890,530.

Specification of Letters Patent.

Patented June 9, 1908.

Application filed June 12, 1907. Serial No. 378,483.

To all whom it may concern:

Be it known that I, ISAAC SMITH Ross, a citizen of the United States, and a resident of Woodward, in the county of Woodward and State of Oklahoma, have invented a new and Improved Device for Identifying Garments and Headwear, of which the following is a full, clear, and exact description.

The purpose of this invention is to provide a novel, simple device that is especially well adapted for readily and conspicuously marking temporarily, a coat, hat or umbrella, that may be hung or placed exposed closely to like articles belonging to other persons, in places for public assemblies, and thus facilitate the sure identification of one's personal wear or property, without an objectionable examination of the belongings of other persons. And, furthermore, to instantly indicate to other parties that they have selected a wrong article of wear or umbrella by mistake.

The invention consists in the construction, combination and arrangement of details, as hereinafter described and defined in the appended claims.

Reference is to be had to the accompanying drawings forming a part of this specification, in which similar characters of reference indicate corresponding parts in all the views.

Figure 1 is a perspective view, showing the device as applied upon a hat for its identification; Fig. 2 is a side view of the device somewhat enlarged, and applied upon the lapel of a coat; Fig. 3 is a detached enlarged side view of the complete device, Fig. 4 is a transverse sectional view of a check or badge in medallion form, and Fig. 5 is an enlarged perspective view of the pin.

The invention briefly described comprises a check or badge 5, a spring clasp 6, a novel hanger pin 7, and a chain 8, that serves to connect the other parts and hold the badge in position for its conspicuous display.

The badge is preferably constructed as shown in the drawings, and consists of a plate metal case 5, cut and stamped into circular form, and rendered concave on one side as appears in Fig. 4, the opposite side being convex correspondingly.

Within the shallow chamber *a*, afforded by the concavity at one side of the case 5, an address card *b* is placed, that is held in place by a spring ring *c*, and indicates the owner-

ship of the article whereon the badge is placed, as will presently be fully explained.

Upon the rim of the case 5, a ring eye *d* is formed or secured, and upon the convex back surface of said case a hook *e* is secured by one end so as to depend below the ring *d*, as shown best in Figs. 3 and 4.

The spring clasp comprises a looped plate metal frame 6, having two substantially parallel jaws, between which a resilient looped plate member *g* is introduced and secured by one end upon one limb of the U-shaped frame 6. A latch limb *h* is pivoted at one end in a slot formed in the opposite limb of the frame 6, and from the pivoted end of the latch limb a short toe *h'* projects through the slot and into engagement with the free end of the looped spring *g*.

It will be seen in Fig. 3, that when the latch limb *h* is rocked so as to lie in the slot, or upon the member of the frame 6 it is pivoted upon, the toe *h'* will press upon the free end of the looped spring *g* and depress it, whereby the clasp is held upon material that may be placed within the looped spring *g*.

The peculiar hanger pin 7, as shown best in Fig. 5, is formed of a single strand of wire rod bent into form as follows. One end portion *i* of the wire strand is pointed at its extremity, as shown at *i'* in Fig. 3, and at a proper distance from this point the wire is bent into a single coil *i*², the portion *i* constituting the pin proper. From the coil *i*², the wire rod is returned toward the point *i'*, and in said material nearly opposite the point *i'*, a lateral bend *i*³ is produced, that affords a keeper hook which receives and holds the pin point, this engagement serving to secure the pin in material it may have been thrust through. Near the keeper hook *i*³, an offset *i*⁴ is bent on the return bent portion of the wire rod, and at said offset a single coil is formed producing a ring *i*⁵. From the keeper hook *i*³, the remaining portion of the wire rod is bent into a curved member *i*⁶, and thence extends toward the coil *i*², thus providing a hook member *i*⁷.

The coupling chain 8 is of sufficient length for a proper connection of the parts 5, 6 and 7, which is effected as follows. One extremity of the chain 8 is secured upon the ring eye *d*, thus connecting the badge therewith. At a suitable point between the ends of the chain, a ring *m* is introduced therein

forming a part thereof, and as shown this ring is coupled with a perforation in one end of the looped frame 6. The remaining shorter portion of the chain 8 is affixed to 5 the ring i^5 , as indicated in Fig. 3, thus completing the connection of the coacting portions of the composite device.

In applying the device for identification of a hat, the spring clasp 6 is hooked upon 10 the free edge of a sweat band A' of a hat A, and the badge 5 allowed to hang pendent, as also may the hanger hook 7, which, however, is indicated by dotted lines as being tucked between the sweat-band and the hat- 15 body; this application of the improvement being represented in Fig. 1.

The arrangement of the device when the hat is hung up is as shown in Fig. 1, which, as shown by dotted lines, will fully expose 20 the badge 5 and indicate the ownership of the hat having the latter hung therefrom.

The hook e on the case of the badge, may be hooked upon the sweat-band A', as shown in Fig. 1, when the device is not in use as a tag, and as the entire appliance is quite 25 small, it will not incommod the wearer of the hat.

It will be obvious that the pendent badge will be so conspicuous that no one but the 30 owner will claim the hat, and, if there are several hats hung closely together, the right hat may be selected by each person upon examination of the address card carried in the case of the tag or badge.

35 In using the device for identifying a coat or like garment B, the hanger pin 7 should be connected by an adjustment of the pin i in the lapel of the coat, either upon the outside or beneath the same, and when not in 40 service the entire device may be concealed by arranging the parts as clearly shown in Fig 2. If the coat is hung up or otherwise deposited while off of the person owning it,

the badge or tag 5 is released from the hook i^7 and allowed to depend from the coat 45 collar, as indicated by dotted lines in Fig. 2.

It will be seen that the different parts of the composite device are coacting, and are of great advantage for the identification of personal wear or other portable belongings, such 50 as an umbrella or other article which may be engaged by the hanger pin.

Having thus described my invention, I claim as new and desire to secure by Letters Patent:

55

1. A device of the class described, comprising a check, a fastening means, a flexible connection between the check and the fastening means, and a supporting means in connection with the check, whereby the check 60 may be supported adjacent to the first-named fastening means or permitted to depend therebelow.

2. A device of the class described, comprising a fastening means, a check having a 65 hook connected thereto, and a flexible connection between the check and the fastening means, whereby the check may be supported adjacent to the fastening means, or permitted to depend there below.

3. A device of the class described comprising a hanger pin having a straight body portion pointed at its free end, a spring coil on one end thereof, an off-set and ring coil at the opposite end, a check having a hook connected thereto, and a flexible connection between the check and pin whereby the check may be supported adjacent to the pin, or permitted to depend there below.

In testimony whereof I have signed my 70 name to this specification in the presence of two subscribing witnesses.

ISAAC SMITH ROSS.
